FOOT TREADLE ELECTRICAL SWITCH

Harry De Jur, New York, N. Y., assignor to De Jur
Amsco Corporation, Long Island City, N. Y., a corpora-
tion of New York

Application June 20, 1957, Serial No. 46,664

Term of patent 14 years

(Cl. D26—13)

Fig. 1

Fig. 2

Fig. 3

Fig. 1 is a rear perspective view of the foot treadle electrical switch showing my new design;

Fig. 2 is a top plan view thereof drawn to an enlarged scale; and

Fig. 3 is a side elevational view thereof, the opposite side being substantially a mirror image thereof.

I claim:

The ornamental design for a foot treadle electrical switch, as shown and described.
